UNITED STATES PATENT OFFICE.

JULIUS C. CHRISTIANSEN, OF ELIZABETH, NEW JERSEY.

COMBINED LADDER AND CHAIR.

1,085,592.

Specification of Letters Patent. Patented Feb. 3, 1914.

Application filed April 23, 1913. Serial No. 763,095.

To all whom it may concern:

Be it known that I, JULIUS C. CHRISTIANSEN, a citizen of the United States, residing at Elizabeth, in the county of Union and State of New Jersey, have invented new and useful Improvements in Combined Ladders and Chairs, of which the following is a specification.

The invention relates to an article of furniture, and more particularly to the class of convertible chairs.

The primary object of the invention is the provision of a chair of this character wherein the back section thereof is formed of hingedly connected parts provided with rungs so that it may be positioned for use as a ladder or for use as the back of the chair, the same being readily detached from the seat of the chair for converting it into a ladder or back.

Another object of the invention is the provision of an article of furniture of this character in which the same can be readily converted into a chair, stool or step ladder, thus affording a piece of furniture useful in a house.

A further object of the invention is the provision of an article of furniture of this character which is simple in construction, readily convertible for the purposes intended thereof, and also which is inexpensive in manufacture.

With these and other objects in view, the invention consists in the construction, combination and arrangement of parts as will be hereinafter fully described, illustrated in the accompanying drawing, and pointed out in the claim hereunto appended.

In the drawing: Figure 1 is a perspective view of the article of furniture, the same being shown for use as a chair. Fig. 2 is a perspective view of the article of furniture converted for use as a ladder. Fig. 3 is a vertical sectional view thereof. Fig. 4 is a perspective view of the article of furniture converted for use as a stool.

Similar reference characters indicate corresponding parts throughout the several views in the drawing.

Referring to the drawing by numerals, the article of furniture comprises a seat bot-

tom 5 constructed in any suitable manner and supported upon vertical legs 6 which are united thereto at the under side of the same in any preferred manner, the marginal edge of the seat bottom 5 being formed with an outwardly extended continuous flange 7 provided at intervals with holes 8 for the detachable connection of a convertible back section presently described.

The back section comprises a two-part frame 9, the parts of which are connected together at their meeting ends by means of hinges 10 so that the said frame 9 can be mounted upon the seat bottom 5 as shown in Figs. 1 and 2 of the drawing.

To permit of the detachable mounting of the two-part frame there are provided at the outer end of its parts dowel pins 11 which are adapted to detachably engage in the holes 8 in the flange 7 on the seat bottom 5 at opposite sides thereof so that when the frame is placed in such position the article of furniture can be used as a ladder, the parts of the frame 10 being formed with spaced cross rungs 12 forming as usual the steps in a ladder.

At one side edge of the parts of the frame 10 are outwardly projecting dowel pins 13 which are adapted to detachably engage in the holes 8 at one side and end of the seat bottom 5 for the use of the frame as a back rest for the chair.

From the foregoing it is thought that the construction and manner of operation of the device will be clearly understood, and therefore a more extended explanation has been omitted.

What is claimed is:—

The combination with a seat having supporting legs, of a pair of sections hingedly connected together, rotatable members carried in the respective sections and having means for engagement with the seat for the fastening of the sections in upwardly convergent relation thereon.

In testimony whereof I affix my signature in presence of two witnesses.

JULIUS C. CHRISTIANSEN.

Witnesses:

G. BARTRAM WOODRUFF,
RUTH DECKER.
